UNITED STATES PATENT OFFICE.

THOMAS F. CASEY, OF WASHINGTON, DISTRICT OF COLUMBIA.

CAN MACHINE.

Application filed July 2, 1925. Serial No. 41,158.

To all whom it may concern:

Be it known that I, THOMAS F. CASEY, a citizen of the United States, residing at Washington, D. C., have invented a new and useful Can Machine, of which the following is a specification.

This invention relates to a machine designed primarily for inserting bottoms in cans prior to the seaming operation, the machine being adapted particularly for use in connection with cans of special shapes such as flat tobacco holding cans.

One of the objects of the invention is to provide a machine of this character adapted to be used in connection with seaming machines such as shown, for example, in Patent No. 810,245 issued on January 16, 1906.

Heretofore, when it has been desired to secure bottoms to cans by the use of a machine such as has heretofore been patented the operator who is employed especially for the purpose, inserts a properly shaped bottom into each can and places the can in a predetermined position but the bottom often becomes misplaced. Consequently the actuation of the machine spoils the can operated on. Furthermore it has heretofore been necessary for the operator to start the machine at the proper times and slowness or negligence on his part results in a considerable loss of time. After the bottom has been secured in the can it has been removed by the operator and placed aside.

One of the objects of the present invention is to avoid all of the objections incident to the operation of machines as heretofore employed by providing a supplemental apparatus for use in connection with the seaming machine, this apparatus working in timed relation with the seaming mechanism so that one operator only is required and his duty is to place the cans in the apparatus with the bottoms positioned thereabove, the mechanism of the apparatus serving to force the bottoms into the cans. Another object is to provide an apparatus which firmly grips the cans during the handling thereof and brings them accurately successively to proper position in the seaming machine after which they are ejected automatically.

Another object is to provide automatic means operated by the said apparatus for starting the seaming machine so that it will properly cooperate with the apparatus forming the present invention.

With the foregoing and other objects in view which will appear as the description proceeds, the invention resides in the combination and arrangement of parts and in the details of construction hereinafter described and claimed, it being understood that within the scope of what is claimed, changes in the precise embodiment of the invention shown can be made without departing from the spirit of the invention.

In the accompanying drawings the preferred form of the invention has been shown.

In said drawings—

Figure 1 is an elevation of the machine, parts being broken away.

Figure 1^A is a view partly in elevation and partly in section of the lower portion of the pedestal of the machine.

Figure 2 is a plan view.

Figure 3 is an elevation of the machine viewed at right angles to Figure 1, the table being broken away.

Figure 4 is a section on line 4—4, Figure 2, portions of the seaming machine being indicated by broken lines.

Figure 5 is a section on line 5—5, Figure 4.

Figure 6 is a section on line 6—6, Figure 2.

Figure 7 is a section on line 7—7, Figure 2.

Figure 8 is an elevation of the ejector.

Figure 9 is a section on line 9—9, Figure 8.

Figure 10 is a section on line 10—10, Figure 2.

Figure 11 is a section on line 11—11, Figure 1.

Referring to the figures by characters of reference 1 designates a hollow pedestal having a base 2 adapted to be secured in place in any manner desired. This pedestal is adapted to be erected close to a seaming machine such as covered by the patent hereinbefore referred to so that the foot pedal of the seaming machine and which has been indicated at A, will extend close to the lower portion of the pedestal. A standard 3 is carried by the base 2 and is connected to the pedestal 1 by a brace 4. This standard has guide arms 5 arranged one above the other and in the lower arm 5 is slidably mounted a plunger 6 the lower end of which is adapted to rest on the pedal A. An ear 7 extends from this plunger and has a rod 8 extending downwardly therefrom and slidable in the

arm 5, this rod extending through a coiled spring 9 one end of which bears against the ear 7 while the other end bears against the lower arm 5. Ear 7, by coming against the lower arm 5 obviously limits the downward movement of plunger 6 while the head 10 on the lower end of the rod, by coming upwardly against lower arm 5, limits the upward movement of the plunger.

10 Plunger 6 has a tongue 11 projecting upwardly therefrom and lapping a tongue 12 extending downwardly from a slide 13. The meeting faces of the two tongues 11 and 12 are serrated as shown at 14 and connecting bolts 15 extend through these portions. Slots 16 are formed in the tongues. Thus it will be seen that by loosening the bolts 15 the tongues can be adjusted relative to each other and by tightening the bolts the parts can be held against relative movement.

15 The upper end of the slide 13 provides a bearing surface for a roller 17 carried by an arm 18 extending radially from a shaft 19 journaled in the upper portion of the standard 3. A finger 20 projects upwardly from this shaft and it will be obvious that each time the finger is shifted in one direction the pin 13 and plunger 6 will be depressed so as to force the pedal A downwardly and thus 25 start the seaming machine of which the pedal is a part. As soon as the finger 20 is released, however, the spring 9, which has been placed under compression, will return the plunger 6, slide 13, arm 18 and finger 20 30 to their normal positions. The pedal A has means, not shown, for automatically raising it when released so that the seaming machine will stop its operation.

20 Secured to the pedestal 1 is a bracket 21 in which is fastened a stub shaft 22 extending from the pedestal. Journaled on the projecting end of this shaft is a large drive gear 23 adapted to receive motion from any suitable means not shown. The lower portion of this gear is lapped by the finger 20 and extending laterally from the gear close to the periphery thereof is a tappet pin 24 adapted to come against and shift finger 20 once during each revolution of the gear.

25 The pedestal 1 is provided near its top with an annular shoulder 25 constituting a bearing or support for the hub portion 26 of a rotary table 27. As shown in the drawings antifriction bearings 28 may be provided for the table so that it can rotate freely.

30 Formed in the table near its periphery are regularly spaced openings 29 and in each opening is mounted a block 30 the ends of which fit within rabbets 31 as shown particularly in Figure 10. The top faces of the blocks are normally flush with the top of the table but each block has downwardly projecting parallel flanges 32 having channels 33 in their inner faces.

Secured to and upstanding from each of the blocks 30 is the stationary jaw of a can clasp, this jaw being indicated at 34. To one end of the stationary jaw is pivotally connected a movable jaw 35, the point of connection being indicated at 36. A spring 37 is located at the point of connection between the two jaws and serves to hold the jaws normally pressed toward each other so as to grip upon a can placed therebetween. The free ends of the jaws are preferably outwardly turned as shown at 38 so as to diverge in the direction of rotation of the table and which direction has been indicated by an arrow in Figure 2. A finger 39 extends outwardly from the movable jaw 35 and an arm 40 extends from said jaw inwardly past the pivotal point 36 and terminates in an ejecting head 41. The stationary jaw 34 has an opening 42 formed in the upper portion thereof of sufficient size to permit the ejecting head 41 to pass therethrough during the ejection of a can as hereinafter pointed out.

35 Extending downwardly from the table 27 at regular intervals are brackets 43 equal in number to the blocks 30. Each of these brackets has an antifriction roller 44 on the back face thereof and these rollers are adapted to be engaged successively by a shifting pin 45 extending radially from the gear 25. Thus once during each rotation of the gear 23 the pin 45 comes against one of the rollers 44 and moves the table about its central bearing a distance substantially equal to 100 the distance between the centers of the blocks 30.

40 A socket 46 is formed in the pedestal 1 below the shoulder 25 and this socket is adapted successively to receive rollers 47 mounted at the inner ends of locking bolts 48. These bolts are regularly spaced around the pedestal and each of them is slidable within a guide 49. A bell crank 50 is operatively connected to each bolt 48 and is pivotally mounted as at 51 on the bottom of the table 27. These bell cranks are regularly spaced and to the outer end of each of them is pivotally connected a rod 52 one end of which is offset downwardly as shown at 53 and shaped to form a flat tongue 54 slidably within the adjacent bracket 43. This rod 52 is slidable within a guide 55 and a spring 56 mounted on the rod bears at one end against the guide and at its other end against a collar on the rod, thus to hold the tongue 54 normally projected beyond the roller 44. This projection of the tongue, however, can only take place when the bolt to which the tongue is operatively connected is seated in the socket 46. This one projected bolt thus serves to hold the table against rotation as will be obvious. When the gear 23 rotates, however, for the purpose of shifting the mechanism, the pin 45 will 130

first come against the projecting end of the tongue 54 and push said tongue forwardly. This will result in the actuation of the bell crank 50 and the withdrawal of the bolt 48 from the socket 46. Immediately following this withdrawal of the bolt and the consequent unlocking of the table, pin 45 comes against roller 44 and pushes the table a sufficient distance to bring the next bolt 48 close to the socket 46, the pin 45 passing out of engagement with the roller 44 just prior to the relocking of the table. As a matter of fact the actuation of the table stops before the bolt is in proper alignment with the socket 46. In order to bring the table to position to insure movement of the bolt into the socket there is provided in the pedestal 1 a spring pressed cam 58, shown in Figure 5, which bears against rollers 59 carried within a groove 60 formed in the hub 26. The parts are so located that when the movement of the table under the impulse of the pin 45 stops, the cam 58, by pressing on one of the rollers 59 will shift the table until said cam bears against two of the rollers as shown in Figure 5. This movement will be sufficient to bring the bolt 48 into alignment with the socket.

A pair of standards 61 and 62 are secured within the upper portion of the pedestal 1 and extend above the table. One of these standards extends radially over the table as shown at 63 and is provided, at its outer end, with a hanger 64. A rotatable shaft 65 is journaled in this hanger and in the overhanging portion 63 of standard 62. To the lower end of this shaft is secured a frame 66 which extends inwardly over the table and carries a roller 67. This roller is normally supported in the path of the fingers 39. A stop pin 68 extends from the hanger 64 into the path of the frame 66 to limit the swinging movement of the frame in one direction and a spring 69 mounted on shaft 65 serves to hold the frame normally pressed against the stop. When the frame is moved away from the stop when subjected to pressure by one of the fingers 39 the spring 69 is placed under stress so that after the finger 39 moves past and out of contact with the roller 67 the spring 69 will automatically return frame 66 to its normal position.

The standard 61 has a radially extended upper portion 70 to the free end of which is connected a guide head 71 in which a slide 72 is mounted for up and down reciprocation. This slide has a slot 73 into which projects one end of a lever 74. This lever is fulcrumed between its ends as shown at 75 and its inner end is pivotally connected, as at 76, to a head 77 adjustably mounted on a rod 78. This rod extends downwardly into the pedestal 1 and is pivotally connected at its lower end to a crank arm 79 extending from a shaft 80. This shaft is jour-

naled in the pedestal 1 and is provided, at its outer end, with a finger 81 supported in the path of a tappet pin 82 extending inwardly from the gear 23.

Slidably mounted on the lower end of the slide 72 is a presser foot 83, there being a slot 84 in slide 72 within which works a pin 85 carried by the presser foot 83. Springs 86 are seated within the presser foot and bear upwardly against the slide 72 so as to hold the presser foot normally extended downwardly relative to the slide 72. A wear plate 87 is secured detachably to the bottom face of the presser foot and is so shaped and proportioned as to fit snugly in the can bottom to be secured to a can.

A bracket 88 is extended from the pedestal 1, as shown in Figure 1 and projects above the table 27 adjacent the presser foot. This bracket supports a fed table 89 which overhangs the table and has a guide loop 90 projecting therebeyond and around the path of the presser foot. An antifriction roller 91 is mounted on the bracket 88 and supports the table 27 adjacent the presser foot so that pressure exerted by said foot will not tend to shift table 27 downwardly out of its proper position.

In Figure 4 the spaced rollers B of the seaming machine have been illustrated in position prior to their application to a can bottom. In this same figure has also been shown the lifting rod C of the seaming machine with its circular head D. The seaming machine is so constructed that each time the pedal A is depressed the rod C is moved upwardly and the rollers B immediately thereafter shifted toward each other and caused to operate on the can bottom so as to produce the proper seam for fastening the parts together.

Gear 23 is adapted to rotate continuously and, as before explained, this continuous operation will result in the intermittent rotation of table 27. Each movement of the table will bring one of the clasps to position under the loop 90 and as it arrives in this position the operator slides a can into the clasp and places a can bottom in the loop 90. After the table has been brought to this position and the can body and bottom properly placed the pin 24 comes against finger 20 and forces plunger 6 downwardly so as to operate the pedal A and set in motion the mechanism of the seaming machine as already explained. Further rotation of the gear will bring pin 82 against and past finger 81 with the result that the presser foot will be operated and will move downwardly against the can bottom and force it firmly into the can body. As soon as the pin passes finger 81 a spring 92 which is connected to lever 74 and to standard 61 will return the parts to their initial positions. Following the actuation of the

presser foot the pin 45 unlocks the table and rotates said table to bring another clasp in position to receive a can body. A can with the bottom in position thereon is ultimately brought above the rod C. Thus when the pedal A is actuated this rod which has been engaged by the grooved flanges 32 during the movement of the clasp to said position, will be moved upwardly, bringing the cam bottom between the seaming rollers B, B. While the can is thus supported the seaming operation will be effected, and the rod C moved downwardly to lower the block 30 to its normal position. The next rotation of the table 27 will withdraw block 30 from the head D of rod C and will bring the finger 39 of the clasp against the roller 67. This roller and its frame 66 will yield in the direction of rotation of the table and against action of spring 69 but will at the same time retard the movement of the finger 39 so that the movable jaw 35 of the clasp will be swung outwardly and the head 41 will move against the can and eject it laterally away from jaw 34 and off of table 27. After finger 39 leaves the roller 67 the jaw 35 will return automatically to its initial position.

What is claimed is:—

- 30 1. The combination with a movable table, of cooperating fixed and movable jaws thereon constituting can gripping means, a tripping element, means projecting from the movable jaw for engagement with the tripping element to shift said jaw and release a gripped can.
- 25 2. The combination with a movable table, of cooperating fixed and movable jaws thereon constituting can gripping means, a tripping element, means projecting from the movable jaw for engagement with the tripping element to shift said jaw and release a gripped can, and ejecting means operated by the movable jaw.
- 40 3. The combination with a movable table, of cooperating fixed and movable jaws thereon constituting can gripping means, a yieldable tripping element supported adjacent the table, and means projecting from the movable jaw for engagement with the tripping element to shift said jaw and release a gripped can.
- 45 4. The combination with a movable table, of cooperating fixed and movable jaws thereon constituting can gripping means, a yieldable tripping element supported adjacent the table, means projecting from the movable jaw for engagement with the tripping element to shift said jaw and release a gripped can, and an ejecting element carried by the movable jaw and shiftable thereby to eject a can from the stationary jaw.
- 50 5. The combination with a movable table, of cooperating fixed and movable jaws thereon constituting can gripping means, yield-

ing means for holding the jaws normally pressed toward each other, a yieldingly restrained tripping element adjacent the table, means on the movable jaw for engagement with said element to swing the movable jaw out of normal position and release the held can.

6. The combination with a movable table, of cooperating fixed and movable jaws thereon constituting can gripping means, yieldingly means for holding the jaws normally pressed toward each other, a yieldingly restrained tripping element adjacent the table, means on the movable jaw for engagement with said element to swing the movable jaw out of normal position and release the held can, and an ejecting device connected to and movable with the movable jaw and through the stationary jaw.

7. The combination with a movable table, of cooperating jaws thereon constituting gripping means, a tripping element, means projecting from one of the jaws for engagement with the tripping element to shift the jaw and release a gripped article, and an ejecting device movable with one of the jaws and relative to the other jaw.

8. The combination with a movable table, of cooperating jaws thereon constituting gripping means, a yieldingly restrained tripping element adjacent the path of the jaws, means projecting from one of the jaws for engagement with the tripping element to shift said jaw and release the gripped article.

9. The combination with a movable table, of cooperating jaws thereon constituting gripping means, a yieldingly restrained tripping element adjacent the path of the jaws, means projecting from one of the jaws for engagement with the tripping element to shift said jaw and release the gripped article, and ejecting means movable with one of the jaws and relative to the other jaw.

10. The combination with a rotatable table, a support therefor, and a plurality of locking bolts for successively engaging the support to hold the table against rotation, of a driving wheel and separate means actuated by the rotation of the wheel for successively unlocking the table and rotating the same.

11. The combination with a table and a support therefor, of a plurality of locking means carried by the table for successively engaging the support to hold the table against rotation, an actuating pin mounted for movement, and separate means for successive engagement by said pin to successively unlock and rotate the table.

12. The combination with a table and a support therefor, of separate locking bolts for successively engaging the support to lock the table against rotation, brackets upon the table, members slidably engaging the brack-

ets and operatively connected to the respective bolts, and a driving pin movable successively against a slidable member and its bracket to successively unlock the table and 5 rotate it.

13. The combination with seaming mechanism including a controlling pedal, of means for supplying cans to said mechanism including a table, a drive wheel, means on 10 the table for holding a can, means operated by the wheel for intermittently actuating the table, and means operated by the wheel for actuating the pedal of the seaming mechanism in timed relation with the movement 15 of the table.

14. The combination with a table, and can holding means thereon, of a drive wheel, means for depressing the pedal of a seaming

machine, and separate means operated by the driving wheel in properly timed relation for actuating the table intermittently and for intermittently shifting the pedal. 20

15. The combination with a table, can holding means thereon, and means for forcing a can bottom into a can on the table, of 25 means for actuating the pedal of a seaming machine, a drive wheel, and separate means operated by the drive wheel for actuating the bottom pressing means, intermittently rotating the table, and actuating the pedal 30 shifting means, all in properly timed relation to feed a can to the seaming machine.

In testimony that I claim the foregoing as my own, I have hereto affixed my signature.

THOMAS F. CASEY.
